McAfee & Finley, Atts.

UNITED STATES PATENT OFFICE

HENRY H. WOTHERSPOON, OF LAWRENCE, MASSACHUSETTS, ASSIGNOR TO MATHIAS KLEIN & SONS, OF CHICAGO, ILLINOIS, A CORPORATION OF ILLINOIS

LINEMAN'S BELT

Application filed August 7, 1931. Serial No. 555,716.

My invention relates generally to linemen's belts.

It is an object of my invention to provide a lineman's belt which shall be comfortable, 5 minimize danger of electric shock to the wearer, and afford to the wearer a high degree of safety.

It is a further object to provide a lineman's belt with a plurality of plies of leather, having the plies stitched together and having the D rings secured to one of the plies.

A further object is to provide a multi-ply leather belt having parts secured thereto by rivets which pass only part way through the belt and thus prevent accidental short circuits through the belt to the body of the lineman.

A further object is to provide an improved 20 lineman's belt in which a portion thereof is conformed comfortably to support the lineman, and made of a leather which will absorb perspiration.

A further object is to provide an improved 25 lineman's belt in which the strain is normally carried by one ply of the belt but in which the other ply of the belt serves as a reserve safety belt in the event that the first ply should tear.

Other objects will appear from the following description, reference being had to the accompanying drawing, in which

Figure 1 is a perspective view of the belt;

Figure 2 is an elevation of the outside of 30 the belt;

Figure 3 is a similar view of the inside of the belt; and

Figure 4 is a longitudinal fragmentary sectional view taken on the line 4-4 of Fig. 2.

The belt of my invention comprises generally two portions, the back support 10 and the strap 12. The back support is composed of a sheet 14, which is preferably latigo leather and the shape of which is indicated 40 generally in Fig. 3, the ends of which are folded back as at 16 about a metallic eye 18. A suitable reinforcing strip 20 is inserted between the portions 14 and 16 and a wedge-shaped piece of leather 22 is inserted between 45 the sides of the reinforcing leather 20 to make

unnecessary any sharp bends in the leather. A pair of rivets 24 secure the metallic eye pieces 18 to the sheet 14 and the reinforcing strip 20 and the leather fillers 22. D rings 23 are pivoted in the eye pieces 18, these rings 55 preferably being integral forgings and having rectangular-shaped openings 25 formed therein.

The strap portion of the belt comprises an outer strap 26 made of a heavy bark tanned flexible leather, one end carrying the usual buckle 28 and the other end being suitably perforated for cooperation with the buckle. A lining strip 30, preferably of latigo leather, 60 is stitched to the end of the strap 26 which carries the buckle 28 and a similar lining 32 is stitched to the perforated portion of the strap 26. Latigo leather has been found to be very satisfactory for the lining, since it is soft and pliable and since, due to its high degree of porosity, its moisture absorbing 65 property is much more pronounced than that of ordinary leather.

The ends of the strap are of uniform width 70 but the intermediate portion which fits about the back of the wearer is of increased width, tapering gradually as indicated in Figs. 2 and 3. The widened portion of the strap is stitched to the back support 14 not only at its 75 marginal edge, as indicated at 34, but also at its ends, as indicated at 36. It will be noted that the strap passes through the rectangular openings 25 in the D rings.

A tool carrying strap 38 is secured to the 80 strap 26 at intervals by rivets 40, the rivets extending only through the strap 38 and the strap 12, but not through the back support 10.

From the above description it will appear 85 that when the belt is in normal use, the strain is transmitted from the D rings to the ends of back support 14, which thus carries substantially the whole load. The strap 26 of course aids in sustaining and supporting the back support 14 by virtue of the fact that it is 90 stitched thereto. If, however, the back support 14 should tear or otherwise give way, the D rings will still be secured to the belt and 95 total failure of the belt thus prevented. The D rings will merely slide along the strap 100

proper and continue to support the linemen.

It will be observed that none of the metallic rivets passes completely through the belt at a place where it might come into contact with the body of the wearer. This construction has considerable value when the belt is being used by electricians working on high voltage lines where there is danger of electrocution should a rivet cause a contact between a source of high potential current and the lineman's body.

While I have illustrated and described a preferred embodiment of my invention, many modifications may be made without departing from the spirit of the invention, and I do not wish to be limited to the precise details set forth but desire to avail myself of all changes within the scope of the appended claims.

1. A lineman's belt comprising a strap having a tapering widened mid-portion adapted to fit about the back of the wearer, a back support of relative soft, porous material secured inside said widened portion of said strap, said back support being of substantially the same shape as the widened portion of the strap, and fastening means secured at the ends of said back support whereby a substantial part of the strain placed upon the belt is sustained by said back support.

2. In a lineman's safety belt, the combination of a support of relative soft, porous material securing it about the wearer and having a widened back portion, a back support of relatively soft, porous leather forming an inner lining for the widened back portion of said strap and having metallic eyes secured at the ends thereof, and D rings having portions pivoted in said eyes and having a slot through which said strap extends.

3. A lineman's belt comprising a main strap having buckle means for securing it about the wearer, a back support having its central portion of considerably greater width than its ends and decreasing gradually in width from said central portion to its ends, said back support being stitched to said belt and having loops at its ends, said loops being formed by turning back the extremities of said back support, rivets securing the bent back portions to the support, D rings pivotally joined to said back support by engagement in said loops, said D rings slidably embracing said strap, a tool holding band, and rivets fastening said band to said strap, said rivets being prevented from contacting with the body of the wearer by said back support, and said rivets securing said loops being prevented from contact with electrical conductors by means of said strap.

4. In a safety belt, the combination of a strap having buckle means for securing the strap about the body of the wearer, a wide back support of relatively soft material stitched to said strap and having metallic

eyes at its ends, said support being tapered in width from its mid-portion to its extremities, and a pair of D rings pivoted in said eyes and slidably mounted on said strap whereby the major portion of the strain is normally carried by said back support and upon tearing of said back support the D rings will support the wearer by their sliding engagement with said strap.

5. A lineman's belt comprising a strap having a widened mid portion adapted to fit about the back of the wearer, a back supporting and perspiration absorbing member secured inside said widened portion of said belt, and conforming generally to the shape thereof, said member being of substantially the same shape as the widened portion of the belt, D rings secured at the ends of said member and embracing said strap, whereby a substantial portion of the strain placed upon the belt is normally sustained by said member, but upon rupture of said member the strain will be carried by said strap.

6. In a lineman's safety belt, the combination of a strap having buckle means for securing it about the wearer and having a widened back portion, a back support of latigo leather, conforming generally to the shape of said portion, forming an inner lining for the widened back portion of said strap and thread stitched thereto, said back support having metallic eyes secured at the ends thereof, and D rings having portions pivoted in said eyes and having a slot through which said strap extends.

7. In a safety belt, the combination of a strap having buckle means for securing the strap about the body of the wearer and having a widened back portion, a back support of leather of relatively great porosity stitched to the widened back portion of said strap and having metallic eyes at its ends, a pair of D rings pivoted in said eyes and slidably mounted on said strap whereby the major portion of the strain is normally carried by said back support and upon tearing of said back support the D rings will support the wearer by their engagement with said strap.

In witness whereof, I hereunto subscribe my name this 3rd day of August, 1931.

HENRY H. WOTHERSPOON.

CERTIFICATE OF CORRECTION.

Patent No. 1,903,081.

March 28, 1933.

HENRY H. WOTHERSPOON.

It is hereby certified that error appears in the printed specification of the above numbered patent requiring correction as follows: Page 2, line 32, claim 2, strike out the words "support of relative soft, porous material" and insert instead the syllable and words "tion of a strap having buckle means for"; and that the said Letters Patent should be read with this correction therein that the same may conform to the record of the case in the Patent Office.

Signed and sealed this 23rd day of May, A. D. 1933.

M. J. Moore.

(Seal)

Acting Commissioner of Patents.
